UNITED STATES PATENT OFFICE.

LOUIS H. WOODCOCK, OF SPOKANE, WASHINGTON.

DISPLAY-RACK.

No. 910,105.

Specification of Letters Patent.

Patented Jan. 19, 1909.

Application filed August 15, 1908. Serial No. 448,660.

To all whom it may concern:

Be it known that I, LOUIS H. WOODCOCK, a citizen of the United States, residing at Spokane, in the county of Spokane and State of Washington, have invented certain new and useful Improvements in Display Racks, of which the following is a specification.

This invention relates to improvements in display racks.

The object of the invention is to provide a rack upon which to display goods used for samples or offered for sale.

A particular object is to provide a display rack that can be used either in a show case, upon shelves or platforms or in any other place where it is desired to show or display goods for sale or samples. In order to accomplish these results, I have provided a display rack of novel construction and adapted to fold in a convenient and novel manner.

For the purposes of illustrating the mechanism and application of my invention, I have shown in the accompanying drawings the application of the rack for use in displaying goods for sale within a show case and have shown and illustrated the manner in which the same can be folded to occupy the proper position within the show case and also the manner in which the rack may be unfolded and drawn from the show case to a convenient position for displaying the goods outside of the show case where the same may be handled or carefully examined.

Figure 1, is an end elevation of the show case with the rack attached thereto, showing a side elevation of the rack elevated to a position convenient for showing goods thereon, together with an end elevation of the same shown in dotted lines within the show case when in a folded position, Fig. 2, is a front elevation of the tray or shelf of the rack and Fig. 3, is a front elevation of the base of the rack.

Pivoted to the bottom 10 of the show case 11 are two standards 12. To the opposite ends of the standards 12 is pivoted the base 13 of the mechanism constituting the rack. The shelf or tray 14 of the rack is supported above the base 13 by the legs 15 pivoted to the underside thereof and to the top of the base 13, the legs 15 being jointed or elbowed at the center thereof and connected by the pins 16. The lower half of the inner legs 15'

are provided with the slots 17 and the lower half of the opposite legs 15² are provided with the pins 18 near the top thereof adapted to slide in the slot 17 of the lower half of the inner legs 15¹. I have shown guards 19 secured to the outer edges of the rack tray or shelf 14 for the purpose of retaining goods upon the same. These guards may be used or left off as desired by the user. The rack is held in its elevated position outside the case 11 by the mechanism shown in Figs. 2 and 3 whereby pins 20 are held in a horizontal position by means of the brackets 21. The pins 20 actuate through holes 22 in the lower portion of the brackets 21. Coil springs 23 encircle the pins 20 and are held in position thereon near the inner ends thereof by means of the lugs 24. Holes 25 are provided in the outer legs 15 near the top thereof and in the outer standards 12 near the top thereof in which holes the pins 20 will enter when the rack is in the expanded position outside the show case as shown in Fig. 1.

When it is desired to fold the rack into the position as shown by the dotted lines in Fig. 1, it is only necessary to withdraw the pins 20 from the holes 25 by pressing together the handles or ends 26 of the pins 20, when the legs 15 will elbow or double at the pins 16, the pins 18 slide downwardly in the slot 17 and the shelf or tray 14 and the base will be brought near together as indicated by the said dotted lines in Fig. 1. When it is desired to again elevate the shelf or tray, it is only necessary to raise the same by hand, draw together the pins 20 by the handles or ends 26 then release the same when the pins 20 are opposite holes 25 when the coil springs 23 contracted between the lugs 24 and the inner brackets 21 will throw the pins 20 into the holes 25 and hold the shelf or tray 14 firmly in position. The bottom 13 of the rack is also sustained in position by the same mechanism whereby the pins 20 engage the holes 25 in the outer standards 12 and are released in the same way. When it is desired to retract the rack into the show case 11, the shelf or tray 14 and the base 13 should first be brought near together by the mechanism described, then the pins 20 released from the holes 25 in the outer standards 12, the rack then pushed into the show case 11 swinging on the pivots 27, whereby the standards 12 and the rack will assume the

position shown by the dotted lines within the show case 11. Within the show case 11, I have shown two shelves 29 to indicate that the rack does not interfere with other displays therein.

Having thus described my invention, what I claim as new and useful and desire to secure by Letters Patent, is:

A display rack, consisting of a shelf or tray at the top, a base underneath the shelf or tray, the shelf or tray and the base connected by legs pivoted thereto and jointed at the middle and adapted to fold so that the shelf or tray and the base may be brought into close proximity with each other, the base supported by standards piv-

oted thereto on the under surface thereof, the standards also pivoted to the bottom of a show case, shelf or other horizontal surface, and means for locking the shelf or tray and base in an elevated position and means of releasing the same and bringing the shelf or tray and base into close proximity with each other and means of folding the same into a show case or onto a horizontal surface, substantially as described.

In testimony whereof I have affixed my signature, in presence of two witnesses.

LOUIS H. WOODCOCK.
